COMBINED CANDLE HOLDER AND CIGARETTE HOLDER

Roxane Kamenstein, 907 5th Ave., New York, N.Y.

Filed Aug. 3, 1960, Ser. No. 61,617

Term of patent 7 years

(Cl. D85—8)

The figure is a front perspective view of a combined candle holder and cigarette holder, embodying my new design.

Except for the area occupied by the handle on the front, the cigarette receiving sockets are substantially equally spaced entirely around the perimeter of the base. The broken line showing of cigarettes is for illustrative purposes only.

I claim:

The ornamental design for a combined candle holder and cigarette holder, as shown and described.
